UNITED STATES PATENT OFFICE

JOHN ROHDIEK, OF NEW YORK, N. Y.

DESIGN FOR A LAMP-SHADE FRAME

Application filed June 28, 1929. Serial No. 31,858. Term of patent 3½ years.

To all whom it may concern:

Be it known that I, JOHN ROHDIEK, a citizen of the United States, residing in New York, in the county of New York and State of New York, have invented a new, original, and ornamental Design for Lamp-Shade Frame, of which the following is a specification, reference being had to the accompanying drawing, forming part thereof.

Fig. 2 is a side view, and

Fig. 3 is a top plan view thereof.

I claim:

The ornamental design for lamp shade frame as shown.

JOHN ROHDIEK.
